INDENTOR TOOL

Oscar H. Mathisen, 1235 Cheltenham Drive, Apt. 2D,
Glen Ellyn, Ill. 60137

Filed June 5, 1967, Ser. No. 7,348

Term of patent 14 years

Int. Cl. D8—02

U.S. Cl. D54—13

FIG.4

FIG.2

FIG.1

FIG.3

FIG.5

FIG. 1 is a side view illustrating relative relationship between the indentor elements, the side opposite that shown in FIG. 1 is a mirror image thereof.

FIG. 2 is a view of the device as seen from the left relative to FIG. 1.

FIG. 3 is a view of the device as seen from the right relative to FIG. 1.

FIG. 4 is a view of the device as seen from the top relative to FIG. 1.

FIG. 5 is a view of the device as seen from the bottom relative to FIG. 1.

I claim:

The ornamental design for an indentor tool, as shown and described.
